(57) **CLAIM**

We claim the ornamental design for the electric plug, as
shown and described.

DESCRIPTION

FIG. 1 is a rear perspective view of an electric plug;
FIG. 2 is a front perspective view of the electric plug;
FIG. 3 is a top plan view of the electric plug;
FIG. 4 is a bottom plan view of the electric plug;
FIG. 5 is a left elevation view of the electric plug;
FIG. 6 is a right elevation view of the electric plug;
FIG. 7 is a front elevation view of the electric plug; and,
FIG. 8 is a rear elevation view of the electric plug.
In the drawings, the broken lines depict unclaimed subject
matter only and form no part of the claimed design.
